UNITED STATES PATENT OFFICE.

DAVID A. GLUSHAK, OF WASHINGTON, DISTRICT OF COLUMBIA.

FOUNTAIN PEN.

Application filed November 9, 1921. Serial No. 514,004.

To all whom it may concern:

Be it known that I, DAVID A. GLUSHAK, a citizen of the United States, residing at Washington, in the District of Columbia, 5 have invented a new and useful Fountain Pen, of which the following is a specification.

The object of my invention is to provide a novel self-filling fountain pen having 10 relatively few parts; to provide a construction in which the inner barrel of the fountain also functions as a suction pump member; to provide means for preventing air bubbles in filling the pen; to provide a construction adapted to increase the capacity 15 of a pen of this type; and to provide the novel combination and arrangement of parts hereinafter described. I attain these and other objects of my invention by the mechanism 20 illustrated in the accompanying drawings, in which:—

Figure 1 is a vertical longitudinal section of a pen embodying my preferred construction;

Fig. 2 is a detail elevational view of same, partly in section;

Fig. 3 is a top plan view of the outer barrel with the inner barrel removed;

Fig. 4 is an enlarged section on line 4—4 30 of Fig. 3;

Fig. 5 is a transverse section on line 5—5 of Fig. 1;

Fig. 6 is a detail section of the end ferrule, with the barrel of the pen shown in elevation 35 detached from the ferrule;

Fig. 7 is the aforesaid barrel;

Fig. 8 is a longitudinal vertical section of another form of my invention having the inner barrel 3 extending substantially 40 the entire length of the outer barrel; and

Fig. 9 is a detail elevational view, enlarged, of the outer knurled end of the barrel shown in Fig. 8.

Like numerals designate like parts in each 45 of the several views.

Referring to the accompanying drawings, I provide an outer barrel 1 having an interior annular shoulder portion 2 near the end of the barrel. I further provide an 50 inner slideable or piston barrel 3 having an annular shoulder portion 4 near its free end, as shown in Figs. 1 and 8, said portion being adapted to abut against portion 2 of the outer barrel when the inner barrel is 55 withdrawn to the limit of its range of movement. To allow of the escape of air from

the chamber between the outer and inner barrel as the inner barrel is withdrawn, I provide the longitudinal channels 8 on the interior of the shouldered portion 2 of the 60 outer barrel, as shown in Figs. 3 and 4. I may provide an end sleeve or cap 6 adapted to be screwed, as at 5, to the suitably threaded portion of the end of the inner barrel, as shown in Figs. 1 and 6; or I may omit 65 sleeve or cap 6 and provide the exposed portion of the inner barrel 3 with a suitably knurled surface 9 to permit of conveniently withdrawing the barrel. To prevent air bubbles forming and causing the 70 spilling of ink, I prefer to provide a suitable rod 7 extending longitudinally of the barrel, approximately centrally thereof, and attached to the interior portion of the end of the barrel. 75

In operation the pen is filled by dipping the point in ink and grasping either the end sleeve 6 or the knurled surface 9 of the inner barrel 3 and withdrawing the inner barrel until its further outward movement 80 is stopped by the contact of its shoulder portion 4 with the shoulder portion 2 of the outer barrel. The inner barrel functions as a piston or suction element to suck up the ink into the barrel 1. The pen is then 85 reversed and the ink flows into the inner barrel 3. The plunger is then pushed back to its original position. In the form of the invention illustrated in Fig. 1, several of the suction or pumping operations are performed to fill the pen, but the pen has a relatively large capacity. In the form of the invention illustrated in Fig. 8, a single 90 operation of the inner barrel 3 suffices to fill the pen. Air in the space between the barrels finds a way of escape through the small channels 8 in shoulder 2. The shoulder 4 fits snugly on or against the surface of the outer barrel. The depending rod 7 on the inner barrel functions to assist the 95 ink in falling down the barrel, prevents air bubbles and counteracts the effect of capillary attraction. This rod, is of approximately the same length as the inner barrel 3 but may be slightly different from 100 it in length.

What I claim is:—

1. In a fountain pen, the combination of 110 an outer barrel having an annular shoulder projecting interiorly near its end, an inner barrel slidably mounted in the outer barrel, said inner barrel having an annular shoul-

der near its inner end projecting outwardly and adapted to abut against the shoulder of the outer barrel, means for the escape of air from the space between the barrels 5 on the outward stroke of the inner barrel, a rod affixed to the inner surface of the end of the inner barrel and extending longitudinally of said barrel for approximately the entire length and spaced from the walls 10 of the barrel.

2. In a fountain pen, the combination of an outer barrel, an inner barrel slidably mounted in the outer barrel and having a small portion thereof projecting beyond the outer barrel, means for limiting the outward movement of the inner barrel, and a rod extending longitudinally of the inner barrel for approximately the length thereof to prevent the formation of air bubbles. 15

DAVID A. GLUSHAK.
